C. D. SMITH.

CARBURETER.

APPLICATION FILED JULY 10, 1914.

1,145,871.

Patented July 6, 1915.

UNITED STATES PATENT OFFICE.

CHARLES D. SMITH, OF DAYTON, OHIO, ASSIGNOR OF ONE-HALF TO LOUIS MORNER, OF DAYTON, OHIO.

CARBURETER.

1,145,871.

Specification of Letters Patent.

Patented July 6, 1915.

Application filed July 10, 1914. Serial No. 850,249.

To all whom it may concern:

Be it known that I, CHARLES D. SMITH, a citizen of the United States, residing at Dayton, in the county of Montgomery and State of Ohio, have invented certain new and useful Improvements in Carbureters; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to certain improvements in carbureters.

The object of the invention is to provide a carbureter having certain structural parts and arrangements whereby a maximum efficiency is obtained and all requirements of a carbureter are subserved to a desired extent.

To the foregoing ends the improvements relate to a needle-valve and the seat thereof, the latter being adjustable relatively to the valve.

The improvements further relate to a rotary valve and its position relative to the mixing tube and through which the primary air admitted to the mixing tube is controlled and regulated. And the improvements further relate to the mounting of the float relative to the inlet valve which is controlled thereby, all as will hereinafter more fully be described, reference being had to the accompanying drawings of which—

Figure 1 is a sectional elevation on the line 1—1 of Fig. 2; Fig. 2 is a sectional view on the line 2—2 of Fig. 1; Fig. 3 is a sectional view on the line 3—3 of Fig. 1; Fig. 4 is an enlarged detail elevation of the needle-valve, adjustable therefor and adjunctive elements; Fig. 5 is a sectional elevation of the automatic air-controlled valve, the needle-valve and the support for the latter; Fig. 6 is a detail view of the positive air-controlled valve; Fig. 7 is a detail view of the valve seat adjusting device.

In a detail description of the invention,

similar reference characters indicate corresponding parts in the several views of the drawings.

The carbureter casing is constructed with a view of accommodating the various elements supported thereby and contained therein. A preferable form of such casing is here shown to consist of a shell 1, a mixing tube 4, an air cylinder 15 and a cap 2. The space within said shell, between the wall 1' thereof and the tube 4, receives the fluid or gasoline, and therein is located a segmental form of float 3 to be again referred to in connection with the main inlet valve through which the fuel is admitted. The tube 4 provides a mixing chamber and penetrating a side of said tube and extending from the float-chamber into said mixing chamber is a tube 5. Upon the upper end of said tube 5, an enlarged tubular member 6 is rigidly mounted upon which is adjustably supported a valve seat 7 which co-operates with a needle-valve 14. There is a continuous passage through the tube 5, its enlarged extension 6, and the needle-valve seat 7. On a side of the needle-valve seat 7, a grooved block 19 is fixed within which a slidable block 20 is mounted by means of a T slot. Engaging the longitudinal slidable block 20 is a pin 21 which is eccentrically mounted in the end of an adjusting screw 22 which penetrates a side of the tube 4. The outer end of the adjusting screw 22 is provided with a head 24 and oppositely arranged shoulders 25 the latter being in a position to engage a stop-pin 25' extending from a side of the tube 4 and thus limiting the turning movement of the screw 22. The needle-valve seat 7 is thus adjustable relative to a needle-valve 14. This valve 14 is mounted on a cross-head 12 which in turn is supported at the upper ends of posts 11 which extend down and are united to a valve 8 which is controlled in its opening movements by the partial vacuum created by the action of the engine which is supplied by the carbureter. The posts 11 extend through a guide-plate 13 as does also the needle-valve 14 said

guide-plate 13 being suitably secured in the upper end of the mixing tube 4.

The air valve 8 seats upon the upper end of a spider 31 that screws into the lower end 5 of the mixing tube 4. A guide-pin 9 penetrates an apertured boss 32 of said spider and also passes through the valve 8 and forms a guide for said valve. A conical spring 10 is placed between the valve 8 and a head 33 10 on the guide-pin 9 and by means of this spring the valve 8 is normally maintained upon its seat. The guide-pin 9 screws through the apertured boss 32 and is, therefore, adjustable to vary the tension of the 15 spring 10.

The primary air inlet is controlled by a rotary valve 16 which is mounted in the cylinder 15 and has a spiral opening 17 extending longitudinally thereof which may communicate with an inlet port 34 which in turn opens into the mixing tube 4. The rotary valve 16 is turned by means of a head 18 and is limited in its rotation by a pin 36 20 which is so arranged as to engage a suitable portion of the cylinder 15.

The shell 1 has a lateral extension 1" into which an apertured plug 37 screws the aperture in said plug terminating in a vertical portion 27 which is controlled by a valve 28 30 mounted in a support 38 extending from the inner extended portion of said plug 37. Also extending from the inner portion of said valve plug 37 is a bifurcated extension 29 between which a float lever 30 is fulcrumed said lever being attached to the float 3. The free end of the lever 30 extends over the end of the valve 28 in a position to close the valve when the float level assumes the requisite position such as is shown in Fig. 1. 40 When the lever frees the said valve 28 by the float falling to a lower level the said valve is then under the influence of the incoming gasoline and the gasoline flows into the float chamber until the requisite level is again attained to shut off the intake.

39 designates a collar screwed on to the outer end of the apertured plug 37 by means of which a fuel inlet nozzle 40 is coupled with the member 37.

50 It will be observed that the apertured plug 37 is conveniently assembled in its operative position with the valve 28 in its position and the inner extension 29 of said plug in a convenient position for inserting the pivot of 55 the float lever 30. The needle-valve seat 7 is movable up or down within certain limits to form a proper opening for the fuel admission.

While I have described minutely the 60 means for adjusting the needle-valve seat, I do not desire to limit myself to the specific means herein shown and described for it is obvious that other means than an eccentric

and slidable block may be employed to effect such adjustment.

Having described my invention, I claim—

1. In a carbureter, the combination with a shell providing a fuel receptacle and a mixing chamber, of an inlet valve controlling the admission of the fuel to said mixing chamber, a seat member for said valve, and means extending laterally from said valve seat member to the exterior of the shell for adjusting said valve seat relatively to the valve.

2. In a carbureter, the combination with a shell providing a fuel chamber and a mixing chamber, of a pipe extending from the fuel chamber to the mixing chamber, a movable valve seat member supported on said pipe within the mixing chamber, means extending laterally from said valve seat member to the exterior of the shell for adjusting said valve seat, and a valve coöperating with said seat and controlling the admission of fuel to the mixing chamber.

3. In a carbureter, the combination with a shell providing a fuel chamber and a mixing chamber, of an air valve controlling the admission of air into the lower end of said chamber, a fuel admission valve connected with said air valve, a movable seat member coöperating with said fuel admission valve, a tube extending from the fuel chamber to the mixing chamber and supporting said movable seat, and means engaging the side of said movable member and extending on the exterior of the shell for adjusting said movable valve seat relatively to the fuel admission valve.

4. In a carbureter, the combination with a shell providing a fuel chamber and a mixing chamber, of a valve controlling the admission of air into the lower end of said mixing chamber, posts extending from said air valve, a crosshead connected to said posts, a needle-valve supported from said crosshead, a movable valve seat member coöperating with said needle-valve, means for adjusting said valve seat member relatively to the needle-valve, said means extending laterally from the valve seat member to the exterior of the shell, and a tube extending from the fuel chamber to said valve seat.

5. In a carbureter, the combination with a shell providing a fuel chamber and a mixing chamber, an air valve mounted in the lower end of said mixing chamber, posts extending from said air valve, a crosshead supported on the upper ends of said posts, a needle-valve supported on said crosshead, a guide member through which said posts and needle-valve project, a movable seat member coöperating with said needle-valve, and means for adjusting said movable valve seat member relatively to the needle-valve co-

operating therewith, comprising a slidable member mounted on the side of said valve seat member.

6. In a carbureter, the combination with
5 a shell providing a fuel chamber and a mixing chamber, said mixing chamber having an elongated air port in a side thereof, a cylinder mounted parallel with the mixing chamber and over said air port, of a rotary
10 air valve mounted in said cylinder parallel

with said mixing chamber and having a spiral air port therein adapted to partially register with the air port in the side of the mixing chamber.

In testimony whereof I affix my signature, 15
in presence of two witnesses.

CHARLES D. SMITH.
